Dec. 1548

Henry Webbard, of New York, N.Y.
Letters Patent No. 1548, dated Mar. 4, 1862.

The schedule referred to in these Letters Patent and making part of the same.

Dec. 1548

To all whom it may concern:

Be it known that I, Henry Hibbard, of the City county and State of New York, have invented a new and original design for ornamenting the handles of Spoons, Forks, and other articles of table ware, and I do hereby declare that the following is a full description of the same, reference being had to the accompanying drawings forming a part of this specification. the same letters of reference, whenever they occur referring to like parts.

Figure 1. is the front side of the spoon.

2. " reverse "

Letter A. is the shield, surmounted by the face of a Ram b. the horns c. of which pass down the back of the shield, and out through its face, so as to encircle the double marginal threads d. d. around the sides of the shield. The space between these marginal threads is concave, and their edges square. Letter e. is an oval circlet, formed at the junction of the shield, and stem f. of the spoon, having in it a representation of a fauns head or face g.

Between the sides of the marginal threads of the shield, is a pine tree cone like device h. This is supported on a staff k. which passes downwards through the upper side of the oval, penetrating the crown of the faun, and out at its mouth, and thence downwards through the lower side of the oval, where it terminates in a vanishing point, in the cantorum space l. between the sides of two broad and outwardly bevelled stems m. covering the larger portion of the surface of the handle.

These stems commence just under the edges of the oval circlet, so as to leave a depressed margin round it, to give greater prominence, and better effect to the design. They thence pass down the handle and terminate at the bowl n. at each side of a raised stem p. having a ball and arrow head device on its lower end.

Letters q. q. are raised marginal threads, commencing at the sides of the oval, at its junction with the shield, by an acute angular outward projection, and thence extends down the sides of the

handle, till they join on to the edges of the shank of the spoon, when they loose themselves, and thus completes the design for ornamenting the front side of the handle of the spoon.

Letter a^2 is the shield of the reverse side of the spoon, surmounted by the crown of a rams head b^2 , the horns c^2 of which encircle double marginal threads d^2 , surrounding the shield, and exposing their tips, on the front side of the spoon, so as to encircle the marginal threads thereon. The space between these marginal threads is concave.

Letter e^2 is an oval circlet, having a centre piece f^2 , composed of five lobes, radiating from a centre point. Surmounting the oval circlet is a short staff g^2 , having an arrow head, below which is a ball, supported on a raised thread or ferrule surrounding the staff.

Letters t^2, t^3 are two square faced marginal threads, commencing at the junction of the shield and stem of the spoon in the like manner as described on the front side of the spoon, and thence running down the edges of the stem till they loose themselves in the edges of the shank of the spoon.

Down the centre of the handle of the spoon is a raised staff, commencing at the lower side of the oval circlet (as if a continuation of the staff g^2 , surmounting it) and terminating at the shank of the spoon in a pine tree cone u^2 , supported in a cluster of five pointed leaves v^2 , bound or held together by a ribbon w^2 of metal, whose flowing ends cover the shank of the spoon to complete the design for ornamenting the reverse side of the handle of the spoon.

Having now described my invention, I will proceed to set forth what I claim and desire to secure by Letters Patent of the United States.

I claim the application and use of the design hereinbefore described for ornamenting the fronts, and backs of the handles of Spoons, Forks and other articles of table ware.
